[57] **CLAIM**

The ornamental design for table lamp, as shown and described.

DESCRIPTION

FIG. 1 is a side elevational view of the table lamp showing my new design;

FIG. 2 is a top plan view thereof;

FIG. 3 is a bottom plan view thereof.

The base of the lamp is substantially symmetrical, but for the switch, the cord loop and the electrical cord.

FIG. 2.

FIG. 1.

FIG. 3.
